John A. Fagerlee

UNITED STATES PATENT OFFICE

JOHN A. FAGERLEE, OF MINNEAPOLIS, MINNESOTA

GARMENT CLEANER

Application filed April 3, 1929. Serial No. 352,155.

This invention relates to devices for cleaning garments, and the primary object is to provide a table or tailor's bench with means whereby a conventional vacuum cleaner, such as is ordinarily used for cleaning rugs and carpets, may be employed in a simple, efficient and practical manner for cleaning garments or other fabric articles that are light enough in weight to be conveniently manipulated by hand. Further and more specific objects will be disclosed in the course of the following specification, reference being made to the accompanying drawing, in which:

Fig. 1 is a top or plan view of a portion of a tailor's bench, showing my attachment as applied thereto.

Fig. 2 is a front elevation, as on the line 2—2 in Fig. 1.

Fig. 3 is a bottom plan view of the attachment, as seen when detached from the bench.

Referring to the drawing more particularly and by reference characters, 4 designates a bench or table in one edge of which has been cut a rectangular opening 5. A plate 6 is placed over the opening 5 and is larger than the latter so that it will rest, at three sides, upon the bench 4. The plate is provided with suitable lugs 7 that fit into the corners of the opening 5 so as to hold the plate stationary upon the bench.

A vacuum cleaner A is reversed, the usual lower side up, and is secured up under the plate 6 by straps 8, 9 and 10. The straps 8 and 9, which are crossed under the suction head of the cleaner, fasten to slotted brackets 11, which brackets are adjustably secured to the plate 6 so that they may be regulated to accommodate various kinds and sizes of cleaners. The strap 10 is anchored to brackets 12 so that it may pass under the rear or motor end of the cleaner. To assist in rigidly securing the cleaner A with respect to the plate 6 I provide the latter with two small slots 13 which may be engaged by the rollers 14 of the cleaner.

The plate 6 is provided with a transversely extending slot 15 that registers with the usual suction slot of the cleaner, and this slot 15 is preferably provided with a screen 16 which will permit the passage of dust and dirt but

will prevent loose ends of the garment from being drawn down into the cleaner under the action of the suction therefrom.

With the device as above constructed and installed, and with the motor of the cleaner running, the clothes or other articles to be cleaned are merely drawn back and forth over the slot 15 until they are thoroughly cleaned of dust and dirt.

It will be understood that this invention does not entirely displace well known methods of cleaning such as steam and so-called "dry" cleaning, which methods are particularly intended for removing grease spots, stains, etc., that a mere suction will not accomplish, but it does provide means for effectively removing dust and dirt, and if there are any stains or spots on the garments they can frequently be removed by local treatment, thus eliminating the necessity of subjecting the entire garment to steam or other cleaning treatment.

It is further understood that suitable modifications may be made in the general design and structural details of the invention as herein shown, provided, however, that said modifications come within the spirit and scope of the appended claims.

Having now therefore fully shown and described my invention, what I claim to be new and desire to protect by Letters Patent is:

1. A cleaning apparatus comprising a plate adapted to fit over an opening in a work table, said plate having formed therein a slot, and means attached to the plate to releasably secure a vacuum cleaner thereto with the suction nozzle under the slot to effect a suction draft through said slot.

2. A cleaning apparatus comprising a plate adapted to fit over an opening in a work table, said plate having formed therein a slot, and straps carried by the plate for releasably securing a vacuum cleaner thereto with the suction nozzle under the slot to effect a suction draft through said slot.

3. A cleaning apparatus comprising a plate adapted to fit over an opening in a work table, said plate having formed therein a slot, and means attached to the plate to releasably secure a vacuum cleaner thereto with the suc-

tion nozzle under the slot to effect a suction draft through said slot, said means including slotted brackets connected by flexible members passing under the vacuum cleaner.

5. A cleaning apparatus comprising a plate adapted to fit over an opening in a work table, said plate having formed therein a slot, and means attached to the plate to releasably secure a vacuum cleaner thereto with the suction nozzle under the slot to effect a suction draft through said slot, said means including adjustable bracket members, and straps connecting the bracket members.

10. A cleaning apparatus comprising a plate adapted to fit over an opening in a work table, lugs depending from the plate for retaining engagement with the table, said plate having an opening, and means carried by the plate for releasably securing a vacuum cleaner thereto with the suction nozzle registering with the opening to effect a suction draft therethrough.

In testimony whereof I affix my signature.
JOHN A. FAGERLEE.
